W. R. MAXEDON

CONTAINER FOR MUCILAGE, PASTE, AND THE LIKE.

Filed Aug. 9, 1924

INVENTOR:
William R. Maxedon

BY
O. V. Maxedon
ATTORNEY.

UNITED STATES PATENT OFFICE.

WILLIAM R. MAXEDON, OF DAYTON, OHIO.

CONTAINER FOR MUCILAGE, PASTE, AND THE LIKE.

Application filed August 9, 1924. Serial No. 731,157.

To all whom it may concern:

Be it known that WILLIAM R. MAXEDON, a citizen of the United States, residing at Dayton, in the county of Montgomery and 5 State of Ohio, has invented new and useful Improvements in Containers for Mucilage, Paste, and the like, of which the following is a specification.

My invention relates to containers for 10 mucilage, paste and the like, including the attachments to the mouth thereof.

More particularly, my invention relates to 15 an ingeniously devised and positioned scraper, by means of which superfluous contents of the container, adhering to the brush used for transferring and applying the same, is readily, easily and conveniently scraped off of the same.

Furthermore, my invention relates to 20 means for preventing the contents of the container from oozing out between the attachments to the mouth thereof, and also the means for suspending the brush in the container.

25 The objects of my invention are: (1) to afford a convenient and inexpensive means of scraping off and getting rid of the superfluous contents of containers for mucilage, paste and the like in the process of transferring said contents by means of a brush from the container and applying the same to the various uses to which and for which the same is designed so that the handle of the brush, the mouth of the container, and 35 the hands and clothing of the user, as well as other things lying close to the container are kept free from being smeared over with the contents of the container; (2) to afford a convenient and inexpensive means for preventing the contents of said container from 40 oozing out and running over the outside of the container in shipping and handling the same in offices and other places where said contents is used in the business and social

45 affairs of life; (3) to afford a convenient and inexpensive means for controlling the brush commonly used in containers for mucilage, paste and the like, so as to make it stand at any desired point in the inside of said 50 container and not fall down to or toward the bottom thereof; and (4) to afford a convenient and inexpensive scraper having the same function and of the same kind described above, and adapted to be applied singly to any container which is not

equipped with a screw lid-shaped collar and a cap at its mouth.

There are other objects that will appear in the further description of my invention.

I accomplish the aforesaid objects by 60 means of the mechanisms hereinafter described wherein the reference characters of the several parts thereof apply to the same part or parts in all figures.

Figure 1 is a perspective view of the container itself together with all attachments to the mouth thereof, as the same are assembled for shipping, and, of course, for sitting on a shelf or desk of an office or other place after shipment. This figure is slightly tilted from an elevation in order to show the horizontal surface of the top of the container. Figure 2 is an elevation of a cross-section of Figure 1, taken on the line $x-x$ of said Figure 1. The brush, however, of Figure 2 stands in elevation. The device shown in Figure 4 is not in this figure. Figure 3 is a perspective of the lid of said container slightly tilted from an elevation so that the device shown in Figure 4 might be seen through the perforation 8, the same being in position for shipping purposes. Figure 4 is a perspective of the device which lies on the top of the member shown in Figures 5 and 6 when prepared for shipment. Figure 5 is a perspective of a threaded cup or lid-shaped collar adapted to screw down upon the top of said container. This figure is slightly tilted from an elevation in order to show the aforesaid scraper before it is bent down for use. Figure 6 is a perspective of the same device shown in Figure 5, the purpose of the figure being to show said scraper bent down for actual use as aforesaid. Figure 7 is a side elevation of a detached portion of Figure 6 taken on the line $a-a$ of said figure. The object of this figure is to show said scraper in its entirety when bent down for use as aforesaid.

1 is a mucilage container prepared for 100 shipment or holding in stock. 2 is the threaded collar that screws down first of all onto the threaded neck of container 1. 3 is the horse-shoe-shaped scraper, having the calk-ends, 12 and 13 thereof, integrally 105 attached and combined with said threaded collar 2. 4 is the elliptical-shaped perforation between the said scraper on the one side and a portion of the collar 2 on the other. 5 is a disc-shaped cover that is adapted to 110

lie on the top of collar 2, or, in other words, to lie in between collar 2 and cap 6. 6 is a threaded cap or lid adapted to screw down upon said collar 2. 7 is the top horizontal face of cap 6. 8 is a perforation through the central point of said cap. 9 is the contents of bottle 1. 10 is the handle, and 11 is the bristle portion of brush 15. 14 is the opening between said scraper 10 3 and a portion of collar 2.

Having thus described my invention in detail and by illustrations, I will now describe it as a working mechanism.

In the factory, container 1 is first filled 15 with whatever contents it is intended to hold. Collar 2 is then screwed down tight upon the neck of the container. The scraper portion 3 thereof is then bent down for use. The disc-shaped cover 5 is then laid down 20 upon the top of said collar 2. Then the cap or lid 6 is screwed down tight onto collar 2 and cover 5. The brush 14 is tied and shipped in a separate package. Said container 1 remains in said condition until it reaches the consumer.

When said container reaches the consumer, the cap or lid 6 is unscrewed and removed, and the disc-shaped cover 5 is also removed. The handle portion 10 of said 30 brush is then run through the perforation 8, which is of a diameter adapted to cause said handle portion to fit tight enough to be readily moved in said perforation, and yet to stand at any fixed point. The handles 35 of some of these brushes are constructed of thin sheet tin, which gives them a degree of diametrical elasticity which greatly facilitates the aforesaid manner of controlling said brush. Said brush having been thus 40 adjusted in said perforation, said cap or lid is then screwed down tight upon said collar 2. In that position it sits on the shelf or desk ready for use.

Then, when being put to use in the office 45 or elsewhere, said cap or lid 6 is unscrewed from said collar 2, and the brush being pushed downward somewhat the bristle portion 11 of said brush is raked back and forth across and upon said scraper 3, until all 50 superfluous contents is removed therefrom, then said bristle portion is applied to the object upon which the contents is intended to be smeared and spread, then, any further adjustment of the brush is easily made. 55 The said lid and brush is then replaced to the position indicated in Figure 2, except the bristle portion only of the brush should extend into the contents of the container. As the contents of said container is being 60 used, said brush is moved a corresponding distance downward, thus adjusting the same so that the said bristle portion only penetrates the contents of said container. It is in this way that the entire contents of said 65 container can be easily, readily and con-

veniently used up without the least particle of the contents thereof ever touching the mouth of said container, the handle portion 10 of said brush, the fingers, the desk, the shelf, or anything else, except the object 70 upon which said contents was designed and intended to be placed and spread.

It is to be noted in this connection that said cap or lid 6 fits so neatly down upon said collar 2, and said brush handle fits so 75 neatly in said perforation 8 as to completely overcome any evaporation of the contents 9.

It is to be noted in this connection also that collar 2 and cap or lid 6 when made up in assorted sizes can be pressed or hammered down upon and adjusted to almost any container and be used in the same manner as described aforesaid.

It is to be noted that the special function of said cover 5 is to prevent the contents of said bottle from escaping through said perforation 8 when being handled in loading, shipping and in unloading, and lying in storage as well. The opening 4 is constructed as long and wide as possible in order to give the widest scope possible to the movement of the bristle portion 11 of said brush.

Having thus described my invention in detail, by illustration and as a working mechanism;

What I claim is:

1. In a container for mucilage, paste and the like, a threaded, lid-shaped collar adapted to encircle and to be screwed or driven down upon the mouth thereof, said collar having an oval-ended, elliptical-shaped perforation through the top thereof, the margin of said top at one end of said perforation being slit away from the balance of the margin at that end, said slit-away portion of said margin having the general shape of a horse shoe, the ends thereof corresponding to the calks of said shoe being integrally attached to and combined with the balance of 100 said margin, said slit-away portion of said margin being adapted to be bent down vertically to any desired point for the uses and purposes set forth in the specification.

2. In a container for mucilage, paste and the like, a cap or lid-shaped collar adapted to encircle the mouth thereof, the top of said collar having a perforation therethrough, a portion of the margin of the balance of said top being slit away from the balance thereof, the slit-away portion of said margin at the ends thereof being integrally attached to and combined with the balance of said margin, said slit-away portion being adapted to be bent down vertically to any desired 115 point for the uses and purposes set forth in the specification.

3. In a container for mucilage, paste and the like, a threaded, lid-shaped collar adapted to encircle and to be screwed or driven 120

- down upon the mouth thereof, said collar having an oval-ended, elliptical-shaped perforation through the top thereof, the margin of the balance of said top at one end of said 5 perforation being slit away from the balance of the margin at that end, said slit-away portion of said margin having the general shape of a horse shoe, the ends thereof corresponding to the calks of said shoe being integrally 10 attached to and combined with the balance of said margin, said slit-away portion of said margin being adapted to be bent down vertically to any desired point for the uses and purposes set forth in the specification, 15 in combination with a threaded cap or lid having a perforation centrally located through the top thereof and a brush, said brush having the bristle end thereof inwardly positioned and the handle thereof 20 adjusted in said perforation which is adapted to permit said handle to frictionally slide therethrough and to suspend said brush at any desired point.
4. In a container for mucilage, paste and 25 the like, a cap or lid-shaped collar adapted to encircle the mouth thereof, the top of said collar having a perforation therethrough, a portion of the margin of the balance of said top being slit away from the 30 balance thereof, the slit-away portion of said margin at the ends thereof being integrally attached to and combined with the balance of said margin, said slit-away por-
- tion being adapted to be bent down vertically to any desired point for the uses and 35 purposes set forth in the specification, in combination with a lid having a perforation centrally located through the top thereof and a brush, said brush having the bristle end thereof inwardly positioned and the 40 handle thereof adjusted in said perforation which is adapted to permit said handle to frictionally slide therethrough and to suspend said brush at any desired point.
5. In a container for mucilage, paste and 45 the like, a threaded, lid-shaped collar adapted to encircle and to be screwed down upon the mouth thereof, said collar having a perforation through the top thereof, a portion of the margin of said perforation being slit 50 away from the balance thereof, the slit-away portion of said margin at the ends thereof being integrally attached to and combined with the balance of said margin, said slit-away portion being adapted to be bent down 55 vertically to any desired point for the uses and purposes set forth in the specification, in combination with a disc-shaped cover positioned upon said collar and a threaded cap or lid having a perforation centrally located 60 through the top thereof and being adapted to be screwed down tight upon said cover and said collar.

In testimony whereof I have hereunto set my hand.

WILLIAM R. MAXEDON.
